UNITED STATES PATENT OFFICE

159,179

CONTAINER FOR KEYS OR SIMILAR ARTICLES

Kurt M. Vogel, Fairfield, Conn., assignor to The
Vogel Manufacturing Co., Bridgeport, Conn., a
corporation of Connecticut

Application May 27, 1949, Serial No. 2,911

Term of patent 14 years

(Cl. D17—14)

To all whom it may concern:

Be it known that I, Kurt M. Vogel, a citizen of the United States, residing at Fairfield, in the county of Fairfield and State of Connecticut, have invented a new, original, and ornamental Design for a Container for Keys or Similar Articles, of which the following is a specification, reference being had to the accompanying drawing, forming part thereof.

In the drawing:

Fig. 1 is a perspective view in closed position from the front of the container for keys or similar articles showing my new design.

Fig. 2 is a perspective view showing the container for keys or similar articles in open position, the dot-and-dash lines indicating the position of a key holder secured therein, the same being for illustrative purposes only.

Fig. 3 is a perspective view in closed position from the rear.

Fig. 4 is a sectional view taken along the line 4—4 of Fig. 1.

I claim:

The ornamental design for a container for keys or similar articles, substantially as shown and described.

KURT M. VOGEL.
